UNITED STATES PATENT OFFICE.

WALTER M. ELLETT AND ROLLO M. VICK, OF ALLIANCE, OHIO.

CREDIT-CABINET.

No. 818,082.

Specification of Letters Patent.

Patented April 17, 1906.

Application filed May 10, 1905. Serial No. 268,730.

To all whom it may concern:

Be it known that we, WALTER M. ELLETT and ROLLO M. VICK, citizens of the United States, residing at Alliance, in the county of Stark and State of Ohio, have jointly invented certain new and useful Improvements in Credit-Cabinets; and we do hereby declare that the following is a full, clear, and exact description of the same, reference being had to the annexed drawings, making a part of this specification, and to the numerals of reference marked thereon, in which—

Figure 1 is a front elevation of a portion of a cabinet, showing our invention applied. Fig. 2 is a bottom or under side view showing a portion of one of the credit-slip-holding partitions or plates. Fig. 3 is a perspective view of a single partition or plate.

The present invention has relation to credit-cabinets; and it consists in the novel arrangement hereinafter described, and particularly pointed out in the claim.

Similar numerals of reference indicate corresponding parts in all the figures of the drawings.

In the accompanying drawings, 1 represents a portion of a case which may be of any desired size, reference being had to the size of the cabinet designed to be constructed. The case within itself forms no particular part of the present invention, except that a case must necessarily be employed to successfully carry out the usefulness of our present invention.

To the upright members or portions of the cabinet are attached a series of credit-slip-holding plates 2, which are spaced from each other and held in spaced relation from each other. The credit-slip-holding plates 2 are each provided with tablet-holding flanges 3, which tablet-holding flanges are preferably formed integral with the plates 2. For the purpose of properly closing the different compartments the wires 4 are provided with the crank portions 5, which crank portions are extended beyond the ends of the tablet-holding flanges, as illustrated in the drawings, which tablet-holding flanges are formed of a

length less than the width of the credit-slip-holding plates. The guard-wires 4 are curved between their bearings 6 and are so curved for the purpose of frictionally holding the crank portions 5 in an elevated position, as illustrated in Fig. 1, or in a lowered position, as illustrated in dotted lines, Fig. 2, and in one place in Fig. 1. When the crank portions 5 of the guard-wires are elevated, slips cannot be conveniently placed upon the partitions or plates 2; but when the crank portions 5 are brought into the position illustrated in dotted lines, Fig. 2, said crank portions are brought down and out of the way, so that credit-slips can be easily inserted upon the partitions 2.

In use when it is desired to file a credit-slip, upon which slip credit has been given, the crank portion 5 of the guard-wire is turned down, as illustrated at the John Frank tablet-holding flange, Fig. 1, after which credit-slips can be easily placed upon the partitions 2 carrying the credit given to the party whose name corresponds with the name upon the tablet-holding slip, the crank portion of the guard-wire having been turned down. After the slip or slips have been properly placed upon the partitions the crank portions 5 are elevated, thereby preventing any accidental displacement of the credit-slips. When it is desired to remove any predetermined credit-slip, the crank portion 5 of the guard-wire is turned down and out of the way, after which credit-slips can be easily removed. We do not desire to be confined to any precise arrangement of connecting the guard-wires, as the only object designed is to provide a means for preventing confusion in placing credit-slips in a cabinet containing a series of credit-slip-holding partitions. It will be understood that the first act in order to place a credit-slip and before placing the credit-slip the crank portion of the guard-wires must be turned down, which, in a sense, opens the space between the credit-slip-holding partitions, and the space thus opened is the space through which the credit-slip is to be placed.

Having fully described our invention, what

we claim as new, and desire to secure by Letters Patent, is—

In a credit-cabinet, a case, a series of credit-slip partitions, said credit-slip partitions carrying wires, and the wires provided with 5 crank or angled portions, said crank or angled portions adapted to be held in lowered or elevated positions, substantially as and for the purpose specified.

In testimony that we claim the above we to have hereunto subscribed our names in the presence of two witnesses.

WALTER M. ELLIOTT.
ROLLO M. VICK.
